UNITED STATES PATENT OFFICE.

FRANK A. JONES, OF NEW YORK, N. Y.

DESIGN FOR A BOX.

SPECIFICATION forming part of Design No. 17,851, dated November 1, 1887.

Application filed June 23, 1887. Serial No. 212,331. Term of patent 7 years.

To all whom it may concern:

Be it known that I, FRANK A. JONES, a citizen of the United States, and a resident of New York, in the county of New York and State of New York, have invented a certain new and original Design for Boxes, of which the following is a specification, reference being had to the accompanying drawings, making a part thereof.

10 My new design for boxes is the representation of a framed picture, ready to be hung on the wall or placed on an easel.

15 In the drawings illustrating my newly-designed box, Figure 1 is a view of the box with the cover or top raised. Fig. 2 is a view of the box as it appears with the cover in place.

20 My design consists, essentially, of the frame A, mat B, and picture C, forming the front or top of the box, the sides D and back E of which, constituting the body of the box, are under and within the top, as shown, so that the

box has the appearance of a framed picture, with a deep receptacle at the back of the frame.

25 The design may be varied in certain particulars without changing its essential feature, which is that of a framed picture, as the picture C may be a colored print or photograph, and the frame may be of any pattern desired, and the mat B may be omitted.

30 What I claim is—

The design for boxes herein shown and described, consisting of the frame A, mat B, and picture C, forming the cover or top of the box, and the sides D and bottom E, forming the body of the box within or under the top.

35 Signed at New York, in the county of New York and State of New York, this 15th day of June, A. D. 1887.

FRANK A. JONES.
